DRIP TRAY GUIDE WIRE AND STOP ARRANGEMENT

William R. Jewell, Erie, Pa., assignor to General Electric Company, a corporation of New York

Application July 7, 1949; Serial No. 103,404

4 Claims. (Cl. 312—346)

1
This invention relates to refrigerator cabinets and in particular to drip trays for evaporators thereof.

Household refrigerators of the present day usually contain an evaporating unit that withdraws heat from the refrigerator cabinet. In the course of time, frost accumulates on the evaporating unit, cutting down the heat transfer rate from the air within the cabinet to the evaporator. Due to the accumulation of frost, it is necessary periodically to defrost the evaporator unit to keep the refrigerator operating effectively. A drip tray is usually placed beneath an evaporator unit to collect any water that might drip therefrom and, in particular, to catch all the water that drips therefrom during a defrost period.

Investigation has shown that the refrigerator user will sometimes insert a drip tray at an angle, causing the rear edges thereof to extend askew of the axis of the evaporator unit so that some of the defrost water dripping from the evaporator is not caught by the tray.

It is an object of this invention to provide an arrangement for properly locating a drip tray beneath an evaporator unit.

It is a further object of this invention to provide, in addition to an axial locating device, a convenient stop that aids in properly positioning the drip tray beneath an evaporator unit.

It is a still further object of this invention to provide apparatus for releasably retaining a drip tray beneath an evaporator unit in a refrigerator cabinet.

Considered broadly, this invention comprises a device for releasably positioning a drip tray beneath an evaporator unit in a refrigerator, assuring proper positioning of the drip tray beneath the evaporator, whereby all the water that drips from the evaporator unit is caught in the drip tray.

Further objects and advantages of this invention will become apparent and the invention will be better understood from the following description referring to the accompanying drawing, and the features of novelty which characterize this invention will be pointed out with particularity in the claims annexed to and forming a part of this specification.

Referring to the drawing, Fig. 1 is a front view of the upper interior portion of a refrigerator cabinet showing the location of the drip tray therein; and Fig. 2 is an enlarged perspective view of the evaporator of the refrigerator with a drip tray positioned thereunder.

2
Referring to Fig. 1, a refrigerator cabinet 1 is provided with a storage space 2 in the upper portion of which there is located an evaporator unit 3 having a drip tray 4 thereunder.

The evaporator unit 3 (as shown in Fig. 2) is of a conventional design having a pair of vertical side walls 5, a bottom 6 and a frozen food storage space 7.

A pair of guide rails 8a; 8b are positioned below the evaporator unit to support the drip tray 4. The guide rails 8a, 8b may be secured to adjoining shelves or to vertical walls of the storage cabinet, depending upon the location of the evaporator unit. In the arrangement shown, one of the guide rails 8a is secured to an adjoining shelf 9 in a conventional manner, the shelf and guide rail being supported at the front edge by a bracket 10 which joins a corner 9a of the shelf 9 and the wall 5 of the evaporator unit. The other rail 8b is secured to the inner wall 11 of the refrigerator cabinet by any suitable means. While guide rails 8a, 8b adequately support the drip tray 4, a certain degree of care and attention is necessary in order properly to position the drip tray 4 beneath the evaporator unit 3. It has been found, however, that by adding a guide bracket 12 to each guide rail and using in combination with this bracket 12 a properly constructed drip tray 4, the correct location of the drip tray is mechanically assured.

The brackets 12 each comprise a single piece of wire rigidly secured to the rails 8a, 8b centrally thereof. In order to guide the drip tray into position, each wire is shaped to provide a vertical portion 13, a transverse horizontal portion 14, a longitudinally disposed horizontal portion 15, a rearwardly declined portion 16, a second transverse horizontal portion 17 and a vertical portion 18.

The vertical portion 13 is long enough to provide a securing section 13a whereby one end of the bracket 12 is secured to the rail 8a in any suitable manner, as by welding. The transverse horizontal portion 14 extends from the top of vertical member 13 toward the vertical axial plane of the evaporator unit a distance great enough to allow the side 20 of drip tray 4 to be received thereunder. The bottom of the horizontal portion 14 is positioned above side 20 of guide rail 8a by a distance slightly less than the vertical depth of end wall 21 of drip tray 4. The drip tray 4 is thus positioned between the top of a flange 22 of guide rail 8a and the portion 14. The axially disposed horizontal portion 15 of bracket 12 is at right angles to the plane formed

by the vertical portion 13 and the horizontal portion 14 and extends toward the front of the refrigerator cabinet a convenient distance until it joins the longitudinally arranged rearwardly declined portion 16 which connects the axially disposed portion 15 to the second transverse horizontal portion 17. Horizontal portion 17 is parallel to and substantially the same length as the horizontal portion 14. Horizontal portion 17 extends from the junction of rearwardly declined portion 16 to vertical member 18. The latter member is parallel to vertical member 13 and includes a portion 18a for securing it to the guide rail 8a as by welding. The combination of rearwardly declined portion 16, horizontal portion 17 and vertical portion 18 provides a wide-mouthing entrance to the guide bracket which facilitates locating the side 19 of drip tray 4 between the vertical members 13, 18 and the horizontal portion 15 of the guide bracket.

The drip tray 4, which may be made of any suitable material, has parallel sides 19, 19a each provided with a centrally located elevated portion 23. The portions 23 slide along the inner edge 24 of each axially disposed horizontal portion 15 of the guide brackets and are guided thereby. The horizontal portion 15 of guide bracket 12 cooperates with vertical sides 20 of guide rails 8a, 8b. Thus, horizontal portion 15 and vertical side 20 of guide rails 8a, 8b limit transverse motion of drip tray 4. The portions 23 each are provided with two shoulders 25, 26 which limit the extent of axial insertion of drip tray 4 into the refrigerator cabinet 2; the shoulders 25 or 26 engaging the horizontal portion 14 of support bracket 12 limit rearward motion of the drip tray. Since portion 23 is centrally located along the side 19, 19a, shoulders 25, 26 assure that, no matter which end of the drip tray is inserted into the refrigerator cabinet, the tray is still properly positioned.

In the operation of the subject apparatus, assuming that the drip tray has been removed from the refrigerator cabinet, either end of the tray 4 is rested on the flange portion 22 of the guide rails 8a and 8b. The tray is then pushed toward the rear of the refrigerator cabinet. The end 21a of the tray strikes the under portions of the rearwardly declined sections 16 of the guide brackets, and the tray is guided by the rearwardly declined sections 16. Continued axial movement of the drip tray 4 towards the rear of the refrigerator cabinet causes end 21a to slide under horizontal portions 15. The vertical distance between the bottom of portion 15 and the top edge of vertical sides 20 of guide rail 8a is less than the height of the sides 19, 19a or ends 21, 21a of the tray so that the tray cannot slide over the tops of sides 20 of the guide rails and askew positioning of the tray is prevented. With continued axial movement of the drip tray towards the rear of the refrigerator, shoulders 25 of elevated portions 23 slide between the horizontal portions 15 of the support brackets and sides 20, 20a of guide rails 8a, 8b; ultimately, shoulders 25 of portions 23 strike the horizontal portion 14 of the guide bracket to prevent further axial movement of the tray.

It is to be noted that no matter which end of the drip tray 4 is first inserted into the refrigerator cabinet, the action of the guide bracket on the drip tray in combination with the support of guide rails 8a and 8b is the same, assuring that there is always proper alignment of the drip tray with the evaporator unit within the refrigerator

storage space. With the drip tray located in this manner, the catching of all water from the evaporator unit is assured.

Modifications of this invention will occur to those skilled in the art and it is desired to be understood, therefore, that this invention is not to be limited to the particular arrangement disclosed, but that the appended claims are meant to cover all the modifications within the spirit and scope of this invention.

What I claim as new and desire to secure by Letters Patent of the United States is:

1. In a refrigerator cabinet having an evaporator therein, a drip tray having parallel sides each having a centrally located elevated portion and means for positioning and supporting said drip tray beneath said evaporator comprising, a pair of guide rails positioned below said evaporator, a guide bracket formed from a single piece of wire rigidly secured to each of said guide rails, each of said guide brackets comprising longitudinally spaced vertical portions, the front one of said vertical portions extending above said guide rail a greater distance than the rear one, transverse horizontal portions extending respectively from each of said vertical portions, said horizontal portions being parallel and of substantially equal length and extending toward the corresponding part of the other of said guide brackets, a rearwardly declined portion connected to the front one of said transverse horizontal portions, a longitudinally disposed horizontal portion connecting said rearwardly declined portion to the other of said transverse horizontal portions, said front transverse horizontal portion and said front vertical portion and said rearwardly declined portion forming a wide-mouthing guide wire structure to facilitate the inserting and positioning of said drip tray in said guide brackets.

2. In a refrigerator cabinet having an evaporator therein, a drip tray having parallel sides each having a centrally located elevated portion and means for positioning and axially guiding said drip tray beneath said evaporator comprising, a pair of guide rails having side members positioned below said evaporator, a guide bracket formed from a single piece of wire rigidly secured to each of said guide rails, each of said guide brackets comprising longitudinally spaced vertical portions, the front one of said vertical portions extending above said guide rail a greater distance than the rear one, transverse horizontal portions extending respectively from each of said vertical portions, said horizontal portions being parallel and of equal length and extending toward the corresponding part of the other of said guide brackets, a rearwardly declined portion connected to the front one of said transverse horizontal portions, a longitudinally disposed horizontal portion connecting said declined portion to the rear transverse horizontal portion, said longitudinal horizontal portion and said rear transverse horizontal portion being located above the top edges of said sides of said guide rails a distance less than the height of said drip tray to prevent the latter from being inserted askew.

3. In a refrigerator cabinet having an evaporator therein, a drip tray having parallel sides each having a centrally located elevated portion and means for positioning and limiting the axial insertion of said drip tray beneath said evaporator comprising, a pair of guide rails positioned below said evaporator, a guide bracket formed from a single piece of wire rigidly secured to each

of said guide rails, each of said guide brackets comprising longitudinally spaced vertical portions, the front one of said vertical portions extending above said guide rail a greater distance than the rear one, transverse horizontal portions extending respectively from each of said vertical portions, said horizontal portions being parallel and of equal length and extending toward the corresponding part of the other of said guide brackets, a rearwardly declined portion connected to the front one of said transverse horizontal portions, a longitudinally disposed horizontal portion connecting said declined portion to the other of said transverse horizontal portions, all of said portions cooperating to form a guide and positioning arrangement to facilitate the inserting and positioning of said drip tray in said guide brackets and said rear horizontal portions of said guide brackets cooperating with said elevated portions on said drip tray to limit the axial insertion of said drip tray into said refrigerator cabinet.

4. In a refrigerator cabinet having an evaporator therein, a drip tray having parallel sides each having a centrally located elevated portion and means for positioning and axially guiding said drip tray beneath said evaporator comprising, a pair of guide rails having side members positioned below said evaporator, a guide bracket formed from a single piece of wire rigidly secured to each of said guide rails, each of said guide brackets comprising longitudinally spaced vertical portions, the front one of said vertical por-

tions extending above said guide rail a greater distance than the rear one, transverse horizontal portions extending respectively from each of said vertical portions, said horizontal portions being parallel and of equal length and extending toward the corresponding part of the other of said guide brackets, a rearwardly declined portion connected to the front one of said transverse horizontal portions, a longitudinally disposed horizontal portion connecting said declined portion to the rear transverse horizontal portion, said rear transverse portion and said declined portion being so formed as to position said longitudinally disposed horizontal portion above the supporting portion of said guide rails a distance less than the height of said drip tray including the corresponding elevated portion thereon, said longitudinally disposed horizontal portion interlocking with said tray elevated portion substantially to prevent transverse motion of said drip tray as the latter is slid along said guide rails into the refrigerator.
